UNITED STATES PATENT OFFICE.

ARTHUR CLAYDEN, OF RICHMOND, ENGLAND.

CRANE.

Application filed August 11, 1919. Serial No. 316,648.

To all whom it may concern:

Be it known that I, ARTHUR CLAYDEN, a subject of the King of Great Britain and Ireland, and residing at 1 Red Lion Street, 5 Richmond, in the county of Surrey, England, have invented certain new and useful Improvements in Cranes (for which I have filed an application in England No. 13983, filed Aug. 28, 1917), of which the following 10 is a specification.

This invention relates to devices for use in power or manually operated hoists or cranes having a swinging jib.

The object of the invention is to provide 15 a portable or stationary hoist or crane for general agricultural purposes but which is chiefly intended for simplifying sack-lifting after filling from threshing machines to enable the person who attends to the filling 20 of sacks when threshing by machinery to deliver them into or ready for carts or other places by the use of a single hand operated cord with perfect safety, or by an automatic action of the filled bag itself upon the apparatus 25 during the lifting of the bag.

According to my invention the portable or stationary hoist or crane comprises a platform mounted on wheels and having a vertical standard and a stationary frame; 30 brackets or uprights for carrying friction and clutch gear combined with winding drums; a swinging arm or jib forming part of a truss frame pivotally supported; sets 35 of pulleys arranged in connection with the said members and suitably supported; a lifting rope for the filled bags and a control rope by which the apparatus is put in or out of action each traversing its series of pulleys; and a frictional or positive locking device 40 for the swinging arm or jib.

The winding drums are adapted to be frictionally or positively clutched by co-acting surfaces which may be corrugated and a resiliently arranged or constructed lever is 45 fixed to an eccentric bearing supporting one end of the winding drum shaft which can be revolved by the lever so as to throw the same into or out of gear with a driving shaft; the other end of the said lever is attached to the operator's control rope by 50 which the apparatus is put into or out of action.

Mounted upon the standard is a corrugated drum or wheel which with a corrugated co-acting block connected to a resiliently controlled rod, constitute a positive

locking device for the swinging arm or jib when such is stationary during the lifting of a bag. Arranged in connection with the swinging arm or jib is an oscillatory lever 60 or bars adapted when struck by a bag in its upward movement to automatically act on the control rope to operate the parts to stop the lifting action of the winding means. The corrugated members of the winding 65 gear are provided with spring controlled levers or catches to impart a locked contact when the parts meet.

The accompanying drawings illustrate an embodiment of my invention as power 70 driven by transmission from the portable engine of a threshing set.

In the drawings:—

Fig. 1 is a side elevation.

Fig. 1^a is a detailed view of the friction 75 driving arrangement showing the actuating lever in another position.

Fig. 2 is a plan of the lower or platform part with friction or positive clutch gear combined with winding drums. 80

Fig. 3 is an enlarged plan of means, as shown in the upper part of Fig. 1 for locking the swinging arm or jib.

Fig. 4 is an enlarged detail view of part 85 of Fig. 3 illustrating the pivotal point of the swinging arm or jib.

Fig. 5 is a rear view of the lower part of Fig. 1.

Fig. 6 is a plan of part of positive clutching gear for winding drums as when corrugated surfaces are employed and further showing a platform or bracket pulley support illustrating the running connection of lifting rope therewith; 90

Fig. 7 is a similar view illustrating in 95 part an alternative form of clutch for the winding drums which consists of uncorrugated and co-acting surfaces and further showing the running connection of the control rope with the winding gear and its traverse over guide pulleys upon a platform or bracket support carried at the upper end of the standard upon the main platform of the apparatus and from these to a point within the operator's reach; and 100

Fig. 8 is an enlarged vertical sectional detail showing the eccentric mounting of the drum and the relative positions of the friction element on the driving shaft and the brake block on the platform. 105

In carrying my invention into effect A is a main platform mounted so as to be port-

able on wheels B which are capable of swivelling, but can be held stationary by blocks or wedges C. Upon the platform A is mounted a standard D and carried upon the 5 said standard is a swivelling arm or jib E adapted to have a swinging movement or circular sweep is indicated at E¹ in Fig. 2. The standard D is held in position by a socket connection with the platform A and iron rods a see Fig. 1, and straining wires b see Fig. 2, and said standard may be of metal and circular in order that the jib E may swing round it.

At the rear of the main platform A are 15 fixed brackets or uprights W for carrying in position the winding gear for hoisting the goods, such gear consisting of one or two revolving drums in clutched connection with a rotating element, if a single drum is 20 employed the friction plate or clutch is carried on the drum axis, but two drums are generally employed and these can be arranged to work separately or conjointly.

In the drawings two winding drums are 25 shown with corrugated or uncorrugated clutch plates but as a single lifting rope is used one drum will run idle, while the other is performing its work. These drums F¹ and F² are free to revolve on a shaft F³ which carries a friction clutch wheel G at one end, a dividing circular block d fixed between the said drums and a similar block e positioned at the opposite end to the wheel G, the blocks d and e are adjustable 30 on the shaft F³ by set screws, and act as distance members. At the inner surfaces of the wheel G and block e there is a circular corrugated clutch plate f¹ at the wheel G and a similar plate f² at the block e, and 35 opposite these clutch plates are similar clutch plates g¹ and g², carried by the flanges of the drums F¹ and F² which are slideable on the axis F³. The clutch plates f¹ and g¹, and f² and g² are brought together by hand and 40 held together in any known manner before starting the apparatus into its running action. Or the clutch plates can be fixed in position by projections h¹, h², h³, h⁴, on each of the clutch plates g¹, g², and by levers k¹, 45 k², k³, k⁴, on the clutch plates f¹, f², adapted to engage the aforementioned lugs and to 50 lock the clutches when in use. On the flange of drums F¹ and F² are fixed eyes l¹, l², to which suitable means fixed to the 55 main platform A may be connected for holding the drum stationary when not in use. The shaft F³ is carried at one end in an eccentric bearing which can be revolved so as to throw the wheel G carried on the 60 shaft in or out of gear with the friction element A³ carried by the driving shaft A² and is mounted in the brackets or uprights W which may be bolted to the main platform A. The eccentrically mounted end of 65 the shaft F³ is under the control of the op-

erator to vary the movements of the bearing by a lever K the end J of which is connected to the eccentric. The lever K projects over the main platform A and has fixed to it a vertical bar L having a hook 70 to attach a control rope S to, and on the lever K is an adjustable counter-weight L¹. Below the lever K is fixed a spiral spring L² attached to the lever K by one of its ends and to a supporting member L⁴ fixed upon 75 a bracket W of the winding gear, the function of which is to assist in bringing the lever K quickly back to stop the lifting or winding action by separating the wheel G from the friction element A³ and lowering 80 the wheel G on to the brake block G¹. The bracket W has a support L⁵ for a pulley L³ over which the control rope S passes.

When power driven the driving wheel M is carried on the main axis and is driven 85 from a source of power, such as the portable engine of a threshing set or a suitable engine or motor positioned on the platform A in driving alignment with the wheel M, or by hand lever when operated manually. 90

The jib E is carried on a pivot E¹¹ on the standard D at the front thereof and is arranged on the truss principle to comprise bars E², E³ and E⁸ duplicated or arranged at both sides and bolted together by 95 bolts E⁴ and assembled as shown in Figs. 1 and 4 to carry the pulleys m, n and control cord or rope S and lifting or winding rope T in a central manner in their relation to the main platform A. 100

The lifting rope T, positioned between the horizontal bars E³ and E⁵, after passing over the pulley m proceeds on to and between pulleys P¹, P², P³ and P⁴ carried by a platform or bracket P mounted on the standard D and from them to winding drum F¹, see Figs. 1 and 6. A similar pulley n conducts the control rope S on to and over the pulleys R², R³, R⁴, R⁵, which are carried by a platform R supported by the standard 110 D. Between and at the end of the horizontal bars E³ and E⁵ see Fig. 4 is placed a safety lever N to have a pivotal movement 115 on the bolt E⁶ at the outer end of the jib E for automatically stopping the winding gear. 120

This lever N is of U-shape formation in plan being arranged between the space bars E³ and pivoted therebetween at a point near its vertex on the bolt E⁶, the outer portion 125 of the said lever operating between the vertical bars E⁷ as shown in Fig. 1. The space N¹ between the side portions of the lever N allows the lifting rope T to pass through it and a hook q is fixed to the said lever to take the locking device cord which is operated simultaneously with the control rope S. 130

On the top of the jib E and the hinged end E¹¹ thereof is positioned the locking device Q see Figs. 1 and 3 which is fixed to

the jib E. The device comprises two fixed blocks O and p forming bearings for a sliding spindle O¹ attached at one end thereof to a sliding block p¹ and at the other end 5 thereof to a sliding corrugated clutch Q¹. A spiral spring Q² is placed around the spindle O¹ and between the blocks p and p¹ to force the clutch member Q¹ out of contact with the member Q². A cord Q³ which 10 is worked with the control rope S passes around the front sliding block p¹ and continued under the jib E on to two pulley wheels Q⁴, Q⁵ which are attached to each side of the hinged portion of the jib E. 15 From this point two single cords are used, one Q⁶ continued under jib E and fixed to the safety lever N with an interposed spring Q¹⁰. The second cord Q⁷ is continued downwardly to standard D on platform A. A 20 hook Q⁸ is fixed to standard D to receive loop in cord Q⁷. The member Q⁹ which consists of a corrugated metal wheel is fixed to standard D and clear of jib E to receive the corrugated clutch Q¹. Above the said 25 locking device is fixed the bracket P, as previously referred to, for receiving the lifting rope T. The standard D is drilled for the rope T to pass through. The horizontal pulleys P¹, P² are for angle or horizontal 30 use as fairleads for hauling. The pulleys P³, P⁴ are placed directly over the hinge of jib E. A horizontal pulley P⁵ is fixed at back of standard D level with the drums as a fairlead for hauling. The bracket R, see 35 Fig. 7, is fixed to top of standard, projects in line with lever K and is held in position with a stay iron R¹ see Fig. 1.

To work the machine the clutch surfaces are put into contact or mesh by bringing the 40 clutch surfaces together, the driving belt is attached, (if the machine is power operated) to the driving wheel M which is allowed to run freely, the operator then pulls the control rope S which puts the winding gear in running operation through the action of the lever K throwing the parts into gear when the cord S is pulled, the hauling or lifting rope T having been previously attached to the filled sack before the control is 45 operated, the sack is raised to the height required for placing the sack into a cart or the like into which it is swung or lifted, the action of pulling the control rope S to put the winding gear into operation to lift the goods, also causes the branch portions of the control rope S to operate the locking device by which the movement or swing of the jib E when carrying the lifted bag can be arrested at the required point in the movement or swing of the jib E. The action of the apparatus will continue while the pull is exerted upon the control rope S, but as soon as the pull is taken off the control rope S, the lever K falls by gravity and the 50 action of the spring L², to put the winding

gear out of action so that hauling or lifting is stopped and the bag remains suspended.

It is thought apparent that the lever K controls the drum so that the drum will be actuated for winding, held neutral and 70 braked, for when the rope S is pulled by the operator, the friction wheel G is brought into contact with the pinion above it, which is the driven counterpart, the apparatus being in gear winding takes place, and this 75 continues until the operator withdraws his pull on the rope S, or if he fails to do this and is still holding the rope, the automatic knock-off action comes into use, for as soon as a bag shoulder, in its ascent, comes into 80 contact with the lowered end of the member N (as in dotted position Fig. 1) the pull on the rope S is withdrawn or relaxed, the lever K drops and the wheel G is withdrawn from its pinion and comes into frictional contact 85 with the brake block below it. This is the brake action. The neutral position is met by varying the pull on the rope S which regulates the amount or intensity of the frictional contact. 90

The improved machine can be driven by power as previously referred to or by hand by applying a hand wheel or lever to the main shaft in place of the wheel M, or changing the driving gear to toothed wheels. 95 The machine is self-contained and can be arranged to travel on track, road or field and can be put into general use for hoisting or lifting and other agricultural purposes such as loading sacks of potatoes into carts 100 or the like operations.

Having now described my invention, what I claim as new and desire to secure by Letters Patent is:—

1. The combination of a vertical standard carried by and secured to a base; a swinging jib with pivots therefor mounted on said standard; a guide pulley attached to said jib; a pulley frame supported by the said standard; guide pulleys attached to said frame, winding means carried on a shaft supported on a frame mounted upon said base; an eccentric bearing, supporting one end of the winding shaft, an arm connected to the eccentric bearing; a friction gear member upon the winding shaft; an operable countershaft for driving the winding shaft; a friction gear member upon the countershaft to co-operate with that upon the winding shaft; a flexible member attachable at one end to the load and at the other end attached to the winding means, passing over said guide pulleys; a further guide pulley attached to the said jib; a further pulley frame supported by the said standard; guide pulleys attached to this said frame; a guide pulley attached to the frame of the winding means; and a flexible member having a free end, operable as a control actuation device, passed over the latter guide pulleys, and at 130

its other end attached to the free end of the arm attached to the eccentric bearing, so that when the free end of the control member is pulled the arm is raised and the eccentric bearing is oscillated to put the friction gears in contact to cause the winding shaft to revolve with the countershaft.

2. The combination of a platform, support wheels therefor, a vertical standard 10 carried by and secured to said platform; a swinging jib frame with pivots therefor mounted on said standard; a guide pulley attached to the said jib frame; a pulley frame supported by the top of the said 15 standard; guide pulleys attached to the said frame; winding means in drum form carried on a shaft supported on a frame mounted upon said platform; an eccentric bearing supporting one end of the winding 20 shaft; a lever connected to the eccentric bearing; a friction gear member upon the winding shaft; an operable countershaft for driving the winding shaft; a friction gear member upon the counter-shaft to co-operate with that upon the winding shaft; a 25 flexible member attachable at one end to the load and at the other end attached to the winding means and passing over the said guide pulleys; a further guide pulley attached to the said jib frame; a further pulley frame supported by the top of the said 30 standard; guide pulleys attached to this said frame, a guide pulley attached to the frame of the winding means; and a flexible member 35 having a free end, operable as a control actuation device, passed over the latter guide pulleys and at its other end attached to the free end of the lever attached to the eccentric bearing, so that when the free end 40 of the control member is pulled, the lever is raised and the eccentric bearing is oscillated and puts the friction gears in contact to cause the winding shaft to revolve with the counter-shaft.

45 3. Hoist mechanism as claimed in claim 1 characterised in that the arm connected to and operating the eccentric bearing carries

a weight and is connected to a recoil spring anchored to the frame of the winding means.

4. Hoist mechanism as claimed in claim 50 1, characterised in that oscillatory bars are pivotally mounted on the said jib and are adapted to be actuated by the load when nearing the limit of its upward movement, said bars at their free ends being engaged 55 in working connection with the flexible member forming the control actuation device, so that when the latter is operated to raise the arm attached to the eccentric bearing of the winding means to put the 60 latter into operation, the said bars are drawn down, into working position above the load, against the resistance of a recoil spring interposed in a flexible member attached at one end to the said bars passes 65 over a guide pulley on the jib and at the other end is attached to the vertical standard.

5. The combination in hoist mechanism of a swinging jib, a corrugated cylindrical member stationary relatively to the jib, a corrugated block adapted to co-act with such cylindrical member, means whereby such block is slidably mounted upon the said jib, and means whereby the said block is caused 75 to engage with the said cylindrical member for locking the said jib to said cylindrical member.

6. The combination in hoist mechanism of a swinging jib, a corrugated cylindrical 80 member stationary relatively to the jib, a corrugated block adapted to co-act with such cylindrical member, means whereby such block is slidably mounted upon the said jib, resilient means for normally holding 85 the said block out of engagement with said cylindrical member, and means whereby the said block is caused to engage with the said cylindrical member for locking the said jib to said cylindrical member.

In testimony whereof I have signed my name to this specification.

ARTHUR CLAYDEN.
